UNITED STATES PATENT OFFICE.

EDWIN N. KRAEMER, OF CEDARBURG, WISCONSIN.

VALVE-SPRING RELEASER AND RETAINER.

1,035,974.

Specification of Letters Patent. Patented Aug. 20, 1912.

Application filed May 24, 1911. Serial No. 629,244.

To all whom it may concern:

Be it known that I, EDWIN N. KRAEMER, a citizen of the United States, residing in Cedarburg, in the county of Ozaukee and State 5 of Wisconsin, have invented new and useful Improvements in Valve-Spring Releaseers and Retainers, of which the following is a description, reference being had to the accompanying drawings, which are a part of 10 this specification.

This invention relates to improvements in valve spring removers more particularly adapted for removing, retaining and replacing the coiled springs surrounding the stems 15 of exhaust and other valves of internal combustion engines.

It is necessary to frequently remove exhaust and other valves in order to clean or 20 grind the same and as the valve springs are of considerable strength it is rather difficult to compress the springs to withdraw the cotter pins or other fastening means to remove the valves.

It is one of the objects of this invention 25 to provide a valve spring remover which may be easily positioned and operated to engage and compress a valve spring preparatory to the removal of the valve from the engine.

30 A further object of this invention is to provide a valve spring remover which is simple in construction and operation and is inexpensive to manufacture.

A further object of the invention is to 35 provide a valve spring remover which is adapted to securely hold a valve spring in compressed position when removed from the engine or to compress a new spring to be replaced around the valve stem.

40 A further object of the invention is to provide a valve spring remover which is very compact in size and may be easily folded to occupy but a minimum amount of space.

45 With the above, and other objects in view, the invention consists of the valve spring remover and its parts and combinations as set forth in the claims, and all equivalents thereof.

50 In the accompanying drawing in which the same reference characters indicate the same parts in all of the views Figure 1 is a side view of the improved spring remover showing the manner of inserting the jaws 55 of the device in position preparatory to com-

pressing the spring engaged, the engine to which the spring is connected being shown in section; Fig. 2 is a side view of the valve spring remover and a portion of the valve on a larger scale with the spring in compressed position; parts of the remover broken away and other parts shown in section; Fig. 3 is a top view of the remover; and Fig. 4 is a front view thereof, parts being in section.

Referring to the drawing the numeral 8 indicates a portion of an internal combustion engine and 9 the exhaust valve thereof which is raised or opened by the cam 10. The lower end of the valve stem 11 of the 70 valve 9 rests on top of the cam rod 12 which serves to lift said valve against the tension of the valve spring 13 surrounding the stem of the valve and interposed between the valve casing 14 and a cotter pin 75 and washer 15 carried by the valve stem.

In order to withdraw or replace the cotter pins or other fastening means it is necessary to compress the coiled springs bearing thereon and to accomplish this result 80 the valve spring remover is provided. This remover comprises a pair of like levers 16 pivotally connected at their rear ends to a transverse member 17. The forward ends or jaws of the levers are bifurcated or provided with end recesses 18 to accommodate the stem of the valve when in engagement with the valve spring. The forward ends of the levers are also provided with annular 85 depressions 19 formed on their inner faces to accommodate the end convolutions of the valve springs and the washers to prevent their accidental disengagement with said jaws.

Toggle links 20 interposed between the 95 levers 16 and pivotally connected at their outer ends to the forward end portions of said levers have their inner ends pivotally connected to the inner end of a threaded rod 21 which extends loosely through a 100 medial opening 22 provided in the transverse member 17. The levers are provided with elongated recesses 20' into which the link ends extend and are pivoted to the side walls of the levers forming the recesses. A 105 thumb nut 23 threaded on the outer end of the rod 21 and bearing against the transverse member serves to close or open the jaws of the levers. The bifurcated ends of the levers are somewhat pointed as indicated 110

by the numeral 24 to more easily slip between the convolutions of the springs or adjacent parts.

From the foregoing description it will be seen that in order to remove a valve it is only necessary to straddle the spring ends, turn the thumb screw to compress the springs so that the cotter pins may be withdrawn from the valve stem and then remove 10 the valve.

The spring may be kept in compressed position to be replaced or it may be released from the remover by unscrewing the thumb screw and the remover may be used in connection with other valves.

When not in use the jaws may be closed together and the device will occupy but a small amount of space and may be easily stored away.

20 20 What I claim as my invention is:

1. A valve spring remover, comprising a pair of levers pivotally connected at one end and having bifurcated jaws formed on their opposite free ends, links pivotally connected to the bifurcated end portions of the

levers and to each other, a threaded rod having one end pivotally connected to the ends of the links which are connected together and extending between the pivoted ends of the levers, and a nut threaded on the rod.

2. A valve spring remover, comprising a pair of levers having bifurcated jaws formed on one end, a transverse member connected to the ends of the levers opposite to the jaws and provided with a medial opening extending therethrough, links each pivotally connected at one end to one of the bifurcated end portions of the levers, a threaded rod pivotally connected to the opposite ends of the links and extending through the medial opening of the transverse member, and a nut threaded on the rod and bearing against the transverse member.

In testimony whereof, I affix my signature, in presence of two witnesses.

EDWIN N. KRAEMER.
